CLAIM

The ornamental design for a laser rangefinder as shown and described.

DESCRIPTION

FIG. 1 is a left side elevational view of a laser rangefinder showing our new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a front left side isometric view thereof;

FIG. 8 is a rear left side isometric view thereof;

FIG. 9 is a front right side isometric view thereof; and,

FIG. 10 is a rear right side isometric view thereof.

The broken lines shown are included for the purpose of illustrating portions of the laser rangefinder that form no part of the claim.

1 Claim, 10 Drawing Sheets
